UNITED STATES PATENT OFFICE.

BLANTON M. BOYD, OF CINCINNATI, OHIO, ASSIGNOR TO THE GLOBE AUTOGRAPHIC REGISTER COMPANY, OF CINCINNATI, OHIO, A CORPORATION OF OHIO.

MANIFOLDING DEVICE FOR TYPE-WRITERS.

1,291,385.

Specification of Letters Patent. Patented Jan. 14, 1919.

Application filed April 6, 1918. Serial No. 227,019.

To all whom it may concern:

Be it known that I, BLANTON M. BOYD, a citizen of the United States of America, and resident of Cincinnati, in the county of Hamilton and State of Ohio, have invented a new and useful Improvement in Manifolding Devices for Type-Writers, of which the following is a specification.

My invention relates particularly to a certain type of manifolding typewriter in which a continuous sheet of fan-folded paper is used to produce the superimposed forms and which is fed from a box of folded paper located adjacent to the machine.

An object of my invention is to produce a device which will permit the use of a series of sheets of different grades and colors of paper, furnished from rolls, while simultaneously overcoming the friction of operation created by having to draw a number of sheets of paper from a number of rolls of paper, whereby the machine may be operated freely.

This and other objects are attained in the manifolding device described in the following specification and illustrated in the accompanying drawing, in which:

Figure 1 is a fragmental side elevation of a manifolding device embodying my invention.

Fig. 2 is a rear elevation of my improved device, parts being broken away for convenience of illustration.

Figs. 3 and 4 are fragmental sectional views of details of my invention.

My improved manifolding device consists of a frame 5 adapted to be mounted upon the frame 6 of a typewriter stand 7 and having cross bars 8 which support the ends of rollers 9 upon which the paper rolls 10 are wound, and means 11 for unrolling the rolls of paper sufficiently before feeding the sheets through the typewriter, to produce a slack therein which will permit of easy and rapid feeding operation.

The slack producing means consists of a swinging lever 12 pivotally connected at its upper end with a pivot block 13 which is mounted for forward and backward movement upon a track 14 by means of rollers 15. The block is connected with the carbon carriage 16 of the manifolding typewriter by means of a plate 17 which projects downwardly between upstanding lug 18 and 19 on the block, so as to move the block back

and forth when the carbon carriage is moved back and forth while simultaneously permitting transverse reciprocatory movement of the carriage when the typewriter is operated. Between its ends the lever 12 is 60 guided by rollers 20 and 21 mounted on a rearwardly extending plate 22, and at its lower end it is provided with a roller 23. A spring 24 is provided for assisting in withdrawing the lever 12 from the downwardly projected position, thereby relieving the operator largely of having to move the weight of the lever when the paper is being fed forwardly. At the top of frame 5 rollers 25 are provided, over which the 70 sheets of paper pass from rolls 10, and at the rear of the extension 26 of the typewriter platen carriage, I have provided a roller 27 over which the paper passes onto the carbon carriage.

In order that the sheets of paper may be prevented from falling when they are being threaded through the machine and the carbon sheets are being placed in position, I have provided a detachable bar 28 80 which is held in position by means of spring clips 29 and 30 at each end thereof. The sheets may be thrown back over bar 28 to support them while adjusting the carbon sheets, or the bar may be removed when 85 placing new roll sheets in position. Another feature is the means by which the rolls may be removably mounted in the cross bars 8. Each cross bar has a notch 31 90 therein, into which one end of each of the axles fits. Located outside of each notch is a cup 32 which is held in registration with the axle by a spring 33. Thus the cups normally retain the axle ends in the notches 95 and prevent displacement thereof from the notches except when it is desired to place fresh rolls therein.

In the operation of my improved device, the carbon carriage 16 is moved to the rear, thus bringing the roller end of lever 12 to 100 the dotted line position disclosed in Fig. 1. The sheets from the rolls 10 are then passed over the rollers 25, around the roller 23 and over bar 27. Bar 28 may be detached during this operation, if desired. The sheets 105 are then passed over the platen carriage 26, the carbon sheets being interleaved between the roll sheets, and are then passed over the platen of the typewriter. After the sheets have been 110 written, the interleaved car-

bon sheets are removed by pushing back the carriage 16. This permits the filled in portions of the sheets to be removed and simultaneously brings the lever 12 from the forwardly withdrawn full line slack producing position to the downwardly projected sheet unrolling position. Immediately upon again bringing the sheets to typewriting position upon the platen and as they are filled in, slack is produced, as shown in full lines in Fig. 1, by reason of the forward movement of carbon carriage 16 which lifts and withdraws the lever 12 toward the front simultaneously. Thus the paper feeding mechanism is relieved of the drag which would be occasioned by having to unroll the several rolls each time the sheets are moved up for line spacing, were a slack producing mechanism such as I have disclosed, not provided.

Having thus described my invention, what I claim is;

A typewriter manifolding device comprising in combination with a typewriter.

a frame adapted to mount a series of rolls of paper thereon rotatively, a carbon sheet carriage reciprocally mounted on the typewriter frame at the rear thereof, a lever pivotally connected with the carriage at one end, and a guide adapted to direct the opposite end in engagement with the paper extending from the rolls when the carbon sheet carriage is operated, whereby the sheets will be unrolled from the rolls, and to direct the sheet engaging end of the lever away from the sheets after the unrolling operation to produce a slack therein when the carbon sheet carriage is operated by the movement of the carbon sheets during paper advancing operation of the typewriter.

In testimony whereof, I have hereunto subscribed my name this 4th day of April, 1918.

BLANTON M. BOYD.
